CLEANING APPARATUS FOR THE COOLING SYSTEMS OF ENGINES

Dewey M. Paxton, Phoenix, Ariz., assignor to Industrial Research, Inc., a corporation of Arizona

Application October 11, 1947, Serial No. 779,255

7 Claims. (Cl. 134—56)

1

My invention relates to apparatus for cleaning fluid circulatory systems, and more particularly relates to an apparatus for flushing the water cooling systems of internal combustion engines. It has as a purpose the provision of a portable apparatus which may not only be used in connection with the engines of mobile units, such as motor vehicles, but may be transported and moved into suitable apposition with stationary internal combustion engines such as the light and power units and pumping engines used in rural districts.

A further purpose of my invention is to provide an apparatus for flushing and cleaning the water cooling system of an engine, which utilizes the power of the engine for circulating the cleansing fluid, and requires no other means for impelling the fluid than means commonly found on internal combustion engines.

Another purpose of my invention is to provide an apparatus for the purpose stated, which causes circulating cleansing fluid to flow through the water-cooling system of an engine in a series of sudden rushes of greater than normal velocity, so as to effectively dislodge and carry away the scale and other matter accumulated in the engine radiator, and other parts of the cooling system.

Yet another purpose of my invention is to utilize the vacuum available in the intake manifold of an internal combustion engine for developing surges in the circulation of fluid through the cooling system of an internal combustion engine, so as to increase the hydraulic scouring action of the fluid.

Still a further purpose of my invention is to provide an apparatus in which the cleansing fluid and the matter removed from the cooling system of the engine, are retained wholly within the apparatus, thus rendering the apparatus particularly suited for use in automobile service stations where as a rule no sewerage is provided to drain off liquid from the pavement thereof.

Broadly stated my invention embodies the use of a portable tank provided with suitable means for tapping the water hose connections between the engine jacket and the radiator of an engine, so as to provide circulation of fluid through the tank as well as through the normal channels of the engine cooling system in which circulation is ordinarily impelled either by a water pump forming part of the engine or by thermo-syphonic action of a radiator. A quick-acting valve is installed in the tank circulatory system, operable by a diaphragm in communication with the intake manifold of the engine and, therefore, responsive to the vacuum prevailing in the intake manifold. A vacuum-breaker, also in the tank circulatory system and hydraulically actuated by the fluid therein, intermittently breaks and re-

2

stores the vacuum applicable to the diaphragm, and thereby intermittently closes and opens the quick-acting valve, causing a surge of fluid from the tank to flow through the engine water cooling system at each occurrence of opening of the valve.

I will describe a preferred embodiment of my invention, and will then point out the novel features thereof in my claims. Further useful attainments and advantages of my invention will become apparent as this description proceeds and from the accompanying drawings, illustrative of my preferred embodiment, in which,

In the accompanying drawings:

Fig. 1 is an elevational view, partly in section, of my invention in operative connection with an internal combustion engine, alternative positions of the vacuum breaker being shown in solid and broken lines.

Fig. 2 is a plan view partly in section on an enlarged scale, taken on the line 2—2 of Fig. 1, and showing details of the quick-opening valve and the diaphragm by which it is operated.

Having reference now to the details of the drawings, this embodiment of my invention comprises a tank 5, mounted on castors 6, and provided with an inlet hose 7 and outlet hose 8 for connection to the water cooling system of an internal combustion engine 9 which is shown as having the conventional water jacket 10, radiator 11, water pump 12, and tubular fittings 13 for connecting the water jacket to the radiator by upper and lower hose sections. The hoses 7 and 8 are provided with flexible T ends 14 and 15 which may be secured to the tubular fittings 13 as temporary substitutes for the conventional upper and lower hose sections. The outlet hose 8, which leads to the lower tubular fittings 13, is secured to the tank 5 by means of a fitting 16 which contains a check valve 17 arranged to permit flow only outwardly from the tank 5 to the engine 9.

The inlet hose 7 leads from the upper tubular fittings 13 to a sediment trap 18 secured to the tank 5. The trap 18 is, in turn, connected by a conduit 19 to a vacuum control chamber 20 which is so disposed as to discharge into the tank 5 through a check-valve 21. A closed tank-engine fluid circuit is thus provided by which fluid contained in the tank 5 may pass therefrom through the check valve 17, outlet hose 8, and T 15 to the water jacket 10 and radiator 11, and return thence to the tank 5 through the T 14, inlet hose 7, sediment trap 18, conduit 19, vacuum control chamber 20, and check-valve 21.

A quick-acting valve 22, is mounted in the conduit 19 to open and close the above described tank-engine circuit, and is operated by a push-rod 23 connected to a diaphragm 24 which has its low pressure side in communication with the

vacuum control chamber 20. The valve 22 may be of any suitable quick-acting type, but is preferably a gate-valve as illustrated in Fig. 2, in which an arm 25 is operably connected to the push-rod 23 so as to be arcuately movable thereby around a pivot 26; and a second arm 27, also pivotable on the pivot 26, has a gate 28 secured thereto so as to be arcuately movable to open and close the conduit 19. The distal ends of the arms 26 and 27 are connected by a spring 29 which causes rapid arcuate movement of the arm 27 and of the gate 28 as the arm 25 is moved through a position of alinement with the arm 27.

To obtain a vacuum in the vacuum control chamber 20, an air conduit 30 is suitably secured to the upper portion of the control chamber and leads therefrom to the intake manifold (not shown) of the engine 9. The air conduit 30 is preferably a flexible hose suited to connection with a nipple or other fitting on the intake-manifold, and its point of entry to the vacuum control chamber 20 is protected by a foam-guard 31 to prevent fluid from being carried over to the engine. It is to be understood that while I prefer to have my invention embodied in a self-contained unit comprising only the apparatus described and the internal combustion engine, the air conduit 30 may lead to any suitable vacuum-generating apparatus such as the intake end of an air-compressor or a water faucet inspirator.

A vacuum-breaking system, mounted within the vacuum control chamber 20, comprises a flexible tube 32 connected at its upper end to a fitting 33 in the upper portion of the vacuum control chamber and open therethrough to the atmosphere and provided at its lower end with a ball check-valve 34. A cylindrical float 35 is pivotally mounted within the vacuum control chamber 20, and the flexible tube 32 is so disposed that the check valve 34 rides upon the float 35. As shown in broken lines in Fig. 1, when the float 35 is in raised position it causes the tube 32 to bend upwardly, and thus inclines the check valve 34 so that the ball 36 thereof rolls by gravity from the valve-closing position shown in section in Fig. 1 to a position in which the valve is open to admit air to the vacuum control chamber 20, so as to break the vacuum therein.

To clean the cooling system of an engine, the tank 5 is brought to a position of apposition with the engine 9, and the T's 14 and 15 are substituted for the conventional upper and lower hose sections thereof, the outlet hose 8 being connected to the lower tubular fittings 13, and the inlet hose 7 being connected to the upper tubular fittings. The air conduit 30 is connected to the intake manifold of the engine, or other convenient suction device. The tank 5 having been partly filled with cleansing fluid, such as a caustic solution, and the engine having been started, the suction in the intake manifold of the engine will cause a partial vacuum in the vacuum control chamber 20 which will be effective upon the diaphragm 24 to cause the valve 22 to spring open, thus opening the tank-engine circuit. Fluid will flow from the engine cooling system through the inlet hose 8, sediment trap 18, and conduit 19 to the vacuum control chamber 20, the partial vacuum in the latter augmenting the velocity of flow above the velocity caused by the impulsion of the water pump 12.

Because of the partial vacuum within the vacuum control chamber 20, the check valve 21 tends to remain closed, even under the hydrostatic

pressure of the fluid in the control chamber, and the fluid therefore accumulates in the control chamber and raises the float 35. When the float has attained a position substantially as shown in broken lines in Fig. 1, the ball check valve 34 opens by the action of gravity on the ball 36, and air is admitted through the flexible tube 32 to the control chamber 20, breaking the vacuum therein. Air pressure on the diaphragm 24 thereupon causes the diaphragm to swing the arm 25 to a position in which the quick-acting valve 22 is snapped closed, and fluid flow from the engine cooling system to the control chamber 20 is interrupted. Release of the vacuum in the control chamber also permits the check valve 21 to open, so that the fluid in the control chamber flows to the tank. 5.

During this stage of the cycle of operations, fluid in the engine cooling system will be circulated in the ordinary manner through the water jacket 10 and radiator 11 by the water pump 12 or the thermo-syphonic action of the radiator, but will not be augmented or increased in velocity by flow from the tank 5 or to the vacuum control chamber 20. The check valve 17 prevents the return of fluid from the engine cooling system to the tank 5.

As soon as the fluid level in the control chamber 20 has fallen sufficiently to lower the ball check valve 34 to a position in which the ball 36 again moves to valve-closing position, another cycle of operation begins, characterized again by a surge of cleansing fluid through the engine cooling system when the vacuum in the control chamber 20 attains sufficient strength to open the quick-acting valve 22.

Thus it is manifest that once my apparatus is connected to the engine as described, it will under the vacuum created by the engine itself operate automatically to intermittently surge a cleansing fluid through the cooling system of the engine, and that my apparatus, while portable to facilitate its application to a motor vehicle where space is at a premium such as in automobile service stations, maintains the cleansing fluid, the scale and other matter removed from the water cooling system, wholly within the apparatus, for were they permitted to be discharged onto the pavement of a service station, the resultant flooding can well be imagined, unless such discharge were made directly into a sewer with which few service stations are provided.

It is to be understood that various changes and modifications may be made in the circulatory cleansing apparatus herein described, of which the drawings are illustrative only and indeed in part diagrammatic, without departing from the spirit and scope of my invention as set forth in the appended claims.

I claim:

1. A cleansing apparatus for the water-cooling system of an internal combustion engine, comprising: tank means for a supply of cleansing liquid; means for connecting said tank means to said cooling system to form a circuit; means for creating a partial vacuum in a portion of said circuit; valve means of quick-acting type for suddenly opening and closing said circuit in response to the degree of said partial vacuum to set up surging of the cleansing liquid through the cooling system of the engine to dislodge and carry away scale and other matter in said system; and means for intermittently breaking said vacuum.
2. A cleansing apparatus for the water-cooling

system of an internal combustion engine, comprising; tank means for a supply of cleansing liquid; means for connecting said tank means to said cooling system to form a circuit; means for creating a partial vacuum in a portion of said circuit; valve means of quick-acting type for suddenly opening and closing said circuit; diaphragm means for actuating said valve means in response to the degree of said partial vacuum to set up surging of the cleansing liquid through the cooling system of the engine to dislodge and carry away scale and other matter in said system; and means for intermittently breaking said vacuum.

3. A cleansing apparatus for the cooling system of an internal combustion engine adapted to form a liquid circuit in combination with said cooling system, and having quick-acting valve means for suddenly opening and closing said circuit to set up surging of liquid through the cooling system of the engine to dislodge and carry away scale and other matter in said system; and intermittent vacuum breaking means operative in response to flow through said valve means of a predetermined volume of liquid and inactive when said valve means are closed.

4. A cleansing apparatus for the water-cooling system of an internal combustion engine, comprising: a liquid supply tank; a vacuum control chamber having an outlet to said tank; means for preventing return flow through said outlet to said vacuum control chamber; a first conduit connecting said tank to said cooling system; a second conduit connecting said vacuum control chamber to said cooling system; air conduit means for connecting said vacuum control chamber to the intake manifold of said engine so as to generate a vacuum in said vacuum control chamber; a quick-acting valve for suddenly opening and closing said second conduit to control the flow of liquid therethrough from said tank and said cooling system to said vacuum control chamber; means responsive to variations in the liquid level in said vacuum control chamber for breaking the vacuum therein; and a diaphragm responsive to a decrease in pressure in said vacuum control chamber to open said quick-acting valve, and to an increase in said pressure to close said valve to set up surging of the liquid through the cooling system of the engine to dislodge and carry away scale and other matter in said system.

5. A cleansing apparatus for the water-cooling system of an internal combustion engine, comprising: a liquid supply tank; a vacuum control chamber having an outlet to said tank; means for preventing return flow through said outlet to said vacuum control chamber; a first conduit connecting said tank to said cooling system; a second conduit connecting said vacuum control chamber to said cooling system; said first and said second conduits having T ends adapted to engage the fittings on the water jacket and radiator of said engine in substitution for the hoses normally engaging said fittings; air-conduit means for connecting said vacuum control chamber to the intake manifold of said engine so as to generate a vacuum in said vacuum control chamber; a quick-acting valve for suddenly opening and closing said second conduit to control the flow of liquid therethrough from said tank and said cooling system to said vacuum control chamber; means responsive to variations in the liquid level in said vacuum control chamber for breaking the vacuum therein; and a diaphragm responsive to a decrease in pressure in said vacuum control chamber to suddenly open

65

70

said quick-acting valve, and to an increase in said pressure to suddenly close said valve to set up surging of the liquid through the cooling system of the engine to dislodge and carry away scale and other matter in said system.

5 6. A cleansing apparatus for the water-cooling system of an internal combustion engine, comprising: a liquid supply tank; a vacuum control chamber having an outlet to said tank; means for preventing return flow through said outlet to said vacuum control chamber; a first conduit connecting said tank to said cooling system; a second conduit connecting said vacuum control chamber to said cooling system; air conduit means for connecting said vacuum control chamber to the intake manifold of said engine so as to generate a vacuum in said vacuum control chamber; a quick-acting valve for suddenly opening and closing said second conduit to control the flow of liquid therethrough from said tank and said cooling system to said vacuum control chamber forming an outlet therefrom to atmosphere; a check valve in said tube operable to open responsively to upward flexation thereof; a float 10 in said vacuum control chamber engaging said tube in a manner to cause upward flexation of said tube in response to an increase in liquid level within said chamber; and a diaphragm responsive to a decrease in pressure in said vacuum control 15 chamber to suddenly open said quick-acting valve, and to an increase in said pressure to close said valve to set up surging of the liquid through the cooling system of the engine to dislodge and carry away scale and other matter in said system.

20 35 7. In combination with the liquid cooling system of an internal combustion engine having a pump driven by the engine and circulating liquid through said system a cooling system cleansing apparatus, comprising: a tank containing cleansing liquid; a first conduit connecting the bottom of the tank to a low point in said cooling system; a vacuum control chamber having an outlet to said tank; means to prevent return flow through said outlet to said vacuum control chamber; a second conduit connecting said vacuum control chamber to a high point in said cooling system; a quick acting valve in said second conduit for suddenly opening and closing said second conduit; a conduit connecting said vacuum control 25 chamber to the intake manifold of the engine to set up a vacuum in said vacuum control chamber; a flexible tube in said vacuum control chamber forming an outlet therefrom to atmosphere; a check valve in said tube operable to open responsively to upward flexation thereof; a float in said 30 vacuum control chamber engaging said tube in a manner to cause upward flexation of said tube in response to an increase in liquid level within said chamber; and a diaphragm responsive to a decrease in pressure in said vacuum control chamber to suddenly open said quick-acting valve and to set up surging of the cleansing liquid.
